UNITED STATES PATENT OFFICE.

GUSTAV A. RAKOWSKY, OF DULUTH, MINNESOTA, ASSIGNOR TO AUTOMATIC UNLOADING CAR CO., OF DULUTH, MINNESOTA, A CORPORATION OF MINNESOTA.

DUMP-CAR.

973,210.

Specification of Letters Patent. Patented Oct. 18, 1910.

Application filed December 13, 1909. Serial No. 532,749.

To all whom it may concern:

Be it known that I, GUSTAV A. RAKOWSKY, of Duluth, St. Louis county, Minnesota, have invented certain new and useful 5 Improvements in Dump-Cars, of which the following is a specification.

My invention relates to cars for handling ore, and particularly to the locking devices therefor and is designed as an improvement 10 over the device for the same purpose shown and described in my application for United States Patent, No. 508,493, filed July 19th, 1909.

My invention consists generally in various 15 constructions and combinations, all as hereinafter described and particularly pointed out in the claims.

In the accompanying drawings forming a part of this specification, Figure 1 is a side 20 elevation of a car with my improved locking device applied thereto, Fig. 2 is an inverted plan view, showing the locking mechanism in its locking position, Fig. 3 is a similar view illustrating the locking bolts 25 withdrawn to allow the buckets to dump, Fig. 4 is a side view of the locking mechanism illustrating the manner of mounting it on the walls of the buckets, Fig. 5 is a detail view illustrating the connection between 30 the locking mechanism and the operating piston, Fig. 6 is a view at right angles substantially to the view of Fig. 5.

In the drawing, 2 represents the lower 35 side sills of the car, 3 the upper side sills and 4 and 5 the buckets having trunnions 6 on the side walls 3. These buckets are adapted to tilt toward one another in the manner described in my application above referred to and have open inner ends 40 through which the ore is discharged into the pocket beneath. These buckets tilt by gravity and to lock them in their elevated position I prefer to provide the mechanism which I will now describe in detail.

45 7 represents castings secured to the walls of the bucket 4 and having brackets 8 provided with transverse sockets 9 in which bolts 10 are slidable. The inner ends of these bolts are provided with heads 11 and 50 are movable back and forth in guides 12, secured to the bottom of the bucket. These bolts, there being one on each side of the bucket, are normally held in their projected position by means of springs 13, provided 55 between the heads 11 and guides 14, also

mounted on the bottom of the buckets. The heads 11 have lugs 15 thereon and levers 16 are pivoted at 17 on the guides 12 and are adapted to engage the lugs 15 and force the heads 11 and the bolts 10 toward one another when the levers 16 are oscillated. The outer ends of the bolts 10 are beveled as shown and are adapted to slip into sockets 18 provided in castings 19, which are secured to the side walls of the bucket 5. 60 65 Links 20 are pivotally connected with levers 16 and with a rod 21 which extends therefrom.

The bucket has a flange 23, pivotally connected with a piston rod 24, which has a 70 slotted connection 25 with a piston 26. A trip lever 27 is pivoted at 28 and connected with the end of the operating rod 21, so that when the trip lever is moved upward the operating rod will be actuated to pull the 75 levers 16 to the position indicated in Fig. 3, and withdraw the bolts 10 from the sockets 18. The piston 26 has a cylinder 29 and a tubular guide 30, on which is mounted a casting 31. The casting 31 has a seat 80 32 formed thereon, with which one end of the trip lever 27 contacts. The piston will have a limited movement independently of the rod 24 and the trip lever will have a limited initial movement to trip the locking 85 mechanism before the power is applied to actuate the buckets. This initial movement may be two or more inches or less if desired, according to the stroke necessary to trip the locking mechanism. As soon as the fluid 90 pressure is relieved in the cylinder, the springs 13 will return the levers 16 and bolts 10 to their normal position and when the buckets are dumped and are lifted again to their loading position, the casting 19 will 95 contact with the beveled ends of the bolts 10 and press them inwardly a sufficient distance to allow the bolts to snap into the sockets 18. Beveled surfaces 33 are preferably provided on the castings 19 to contact with the 100 ends of the bolts and insure the automatic relocking of the buckets.

This mechanism I have found to be simple and inexpensive in construction and particularly adapted for dumping cars of this 105 type, as it is protected by the bottom walls of the buckets from injury and at the same time is easily accessible.

I claim as my invention:

1. The combination, with a car frame, of 110

- tilting buckets journaled therein and arranged to tilt inwardly to discharge their load, a locking mechanism provided at the inner ends of said buckets, said locking mechanism including transversely slidable bolts and sockets therefor, and a fluid pressure controlled mechanism for tripping during its initial movement said locking mechanism.
10. 2. The combination with a car frame, of tilting buckets journaled therein and arranged to tilt inwardly to discharge their load, a locking mechanism provided at the inner ends of said buckets and including transversely slidable spring pressed bolts and sockets therefor mounted on said buckets, pivoted levers arranged to engage said bolts and draw them inwardly against the tension of their springs and a fluid pressure controlled mechanism for actuating said levers, substantially as described.
15. 3. The combination, with a car frame, of tilting buckets journaled therein and arranged to tilt inwardly to discharge their load, a locking mechanism secured to the bottom of one of said buckets and including transversely slidable bolts arranged to enter sockets provided in the outer walls of the other bucket, and a fluid pressure controlled mechanism for retracting said bolts and releasing said buckets one from the other, substantially as described.
20. 4. The combination, with a car frame, of tilting buckets journaled therein and arranged to tilt inwardly to discharge their load, a locking mechanism secured to the bottom of one of said buckets near its inner end and including means adapted to interlock with the other bucket and hold both of them in their loading position, and a fluid pressure controlled mechanism for tripping said locking means, substantially as described.
25. 5. The combination, with a car frame, of tilting buckets mounted therein, a locking mechanism provided at the abutting inner ends of said buckets, said locking mechanism including transversely sliding bolts, a rod operatively connected with said bolts for drawing them inwardly when said rod is actuated, a fluid pressure cylinder and piston therefor, and a trip lever connected with said actuating rod and in the path of said piston and adapted to be operated by said piston during its initial movement.
30. 6. In a dump car the combination, with a frame, of tilting buckets journaled therein and arranged to tilt inwardly toward one another to discharge their load, a locking mechanism provided at the meeting ends of said buckets, said locking mechanism being secured to the bottom of one bucket and

having means sliding transversely with respect to its bucket to engage and interlock with the other bucket and means for tripping said locking mechanism to release said buckets.

7. The combination, in a dump car with a frame, of tilting buckets journaled therein and arranged to tilt inwardly toward one another to discharge their load, a locking mechanism secured to the bottom of one of said buckets near its inner end and having means to engage and interlock with the other bucket to hold them in their loading position, said locking means sliding in a plane parallel substantially with the plane of the bucket bottom whereto it is secured and transversely thereof, and means for tripping said locking mechanism to release said buckets.

8. The combination, in a dump car with a frame, of tilting buckets journaled therein and arranged to swing inwardly toward one another to discharge their load, a locking mechanism secured to the bottom of one of said buckets near its inner end and including means adapted to interlock with the other bucket and hold both of them in their loading position, and a fluid pressure controlled mechanism for tripping said locking means, substantially as described.

9. The combination, in a dump car with a frame, of tilting buckets journaled therein and arranged to swing inwardly toward one another to discharge their load, a locking mechanism secured to the bottom of one of said buckets near its inner end and including means adapted to interlock with the other bucket and hold them in their loading position, a fluid pressure controlled mechanism for tilting said buckets and means operatively connecting said fluid pressure controlled mechanism with said locking means for tripping said locking means during the initial movement of said fluid pressure controlled mechanism, and before force is applied to tilt said buckets.

10. The combination, with a car frame, of tilting buckets journaled therein and arranged to tilt inwardly to discharge their load, a locking mechanism provided at the inner ends of said buckets, said mechanism including a transversely movable means and sockets therefor, and a fluid pressure controlled mechanism for tripping said locking mechanism.

11. The combination, with a car frame, of tilting buckets journaled therein and arranged to tilt inwardly to discharge their load, a locking mechanism provided at the inner ends of said buckets, said mechanism including transversely slidable bolts and sockets therefor, and means for moving said bolts lengthwise to release said buckets.

12. The combination, with a car frame, of tilting buckets journaled therein and ar-

ranged to tilt inwardly to discharge their load, spring pressed transversely slidable bolts carried by one of said buckets, the other bucket having sockets to receive said 5 bolts, said bolts slipping automatically into said sockets when said buckets return to their normal loading position, and means for retracting said bolts to release the buckets.

13. The combination, with a car frame, of 10 tilting buckets journaled therein and arranged to tilt inwardly to discharge their load, spring pressed locking means carried

by one of said buckets and adapted to enter sockets provided in the other bucket and thereby normally locking them in a horizontal position, and means for retracting said locking means to release said buckets and allow them to tilt to a dumping position. 15

In witness whereof, I have hereunto set my hand this 8th day of December 1909.

GUSTAV A. RAKOWSKY.
